UNITED STATES PATENT OFFICE.

CARL W. KNIGHT, OF TIFFIN, OHIO.

EXPLOSIVE-ENGINE.

1,082,958.

Specification of Letters Patent. Patented Dec. 30, 1913.

Application filed July 19, 1911. Serial No. 639,457.

To all whom it may concern:

Be it known that I, CARL W. KNIGHT, a citizen of the United States, residing at Tiffin, in the county of Seneca and State of Ohio, have invented a new and useful Explosive-Engine, of which the following is a specification.

This invention relates to improvements in explosive motors, the primary object of the invention being the provision of a reciprocating motor in which the piston head is provided with a series of ports and co-acts with a stationary member inferiorly thereof and concentrically thereof to provide an explosive chamber, the ports of the piston head and of the cylinder being valveless, the piston head during the reciprocation acting as a valve to open carbureted air intake upon the out stroke and due to the compressive action of the piston upon the supply of carbureted air at the upper end of the cylinder to cause the carbureted air to rush into the interior of the piston to supply the explosive chamber thereof with the charge and at the same time to assist in expelling the burnt gases through the exhaust port of the piston and cylinder.

A further object of this invention is the provision of a motor, provided with an inferior stationary cylinder with water-jacketed walls and an exterior casing mounted concentrically thereabout and also water-jacketed, the two co-acting to provide a support for a hollow reciprocating piston, the piston carrying its explosive chamber, and being provided with ports controlled by the reciprocation thereof to admit carbureted air to the explosive chamber and to permit the exhausting of the burnt gases, the said intake and exhausting being entirely due to the reciprocation of the piston.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,—Figure 1 is a vertical central sectional view through a motor constructed according to and embodying this invention, the dotted line illustrating the lower position of the piston. Fig. 2 is a

section taken on line 2—2 of Fig. 1. Fig. 3 is a section taken on line 3—3 of Fig. 1. Fig. 4 is a section taken on line 4—4 of Fig. 1. Fig. 5 is a section taken on line 5—5 of Fig. 1. Fig. 6 is a section taken on line 6—6 of Fig. 1.

Referring to the drawings, the numeral 1 designates the base which carries the lower portion 2 of the crank case, the upper portion 3 thereof being detachably connected to the lower portion as shown and having journaled therein the crank 4, carrying at one end the fly or balance wheel 5.

Connected to and supported by the flanges 6 of the crank case and projecting upwardly therefrom is the inner cylinder 8, composed of the inner casing 9 and the outer casing 10, concentric thereto and providing the water jacketing space 11, said cylinder 8 being provided with the two oppositely disposed vertical slots 12, in which is mounted to vertically reciprocate therein without affecting the walls of the cylinder 8 the cross-head 13, connected to the piston rod 14, which in turn is connected to the crank shaft 4. The cylinder 8 is provided with the inner head 15 and the outer thick walled head 16 which is the lower wall of the explosive chamber, and mounted annularly of the walled head 16 in the cylinder 10, are the packing rings 17.

Surrounding the cylinder 8 and providing a concentric space therearound and also projecting a considerable distance above the head 16 thereof, is the outer cylinder 18, whose inner wall in combination with the outer wall of the cylinder 8 forms a guiding means for the hollow cylindrical piston or head 19, whose upper end is closed at 19', and is connected at 20 to the extreme ends 13' of the cross head 13, whereby the said piston head 19 is connected to the crank shaft 4 for conveying to the crank a rotary movement due to the reciprocation of said piston 19.

Provided in the walls of the piston head 19 and communicating with the interior thereof are the two oppositely disposed ports 21 and 22 and surrounding said piston head 19 above and below said ports are the packing rings 21'. The ports 21 and 22 communicate, when they are in the position as clearly shown in Figs. 1 and 2 with the respective ports 23 and 23', leading through the bypasses 24 through the ports 25 and 25', respectively, into the compartment 26 in the

upper and extreme end of the motor. Provided in the lower skirt portion of the hollow piston head 19, is a large port 27 adapted to align with the exhaust outlet 28, while surrounding the wall 18 is its water jacket 29, at whose base 30, is the inlet conduit 31 which receives its carbureted air from the carburetor or any other form of gas mixing device. Provided in the wall of the cylinder 10 is a port 31' in line with the conduit 31 to permit carbureted air to enter the chamber above the piston upon the down stroke of the piston 19 when the piston uncovers or passes below the port 31', and by reason of 15 the vacuum caused within the chamber 26 between the head 19' and the under side of the top of the cylinder, the carbureted air is drawn through the conduit 31 and port 31' into the chamber 26 to be compressed therein 20 upon the upstroke of the piston head. When the ports 21 and 22 of the piston head, as shown in Fig. 1, align with the ports 23 and 23', the compressed carbureted air will enter the chamber of the piston head and upon the 25 downstroke, the port 22 will align with the port of the spark plug 31'', at the highest point of compression, dotted lines Fig. 1. At this point the compressed charge within the piston chamber is exploded, moving the 30 piston head from the dotted position to the full line position of Figs. 1 and 2, bringing the port 27 of the head 19 to align with the exhaust outlet 28, so that the charge will be exhausted slightly before and during the 35 intake through the by-passes from the chamber 26.

In order to provide the proper circulation of water within the jackets 11 and 30, the chambers formed thereby are in communication with each other through the medium of the two conduits 32 as clearly shown in Fig. 1.

By this means it will be seen that the piston 19 with its respective ports and also the 40 respective ports of the stationary member co-act to discharge and explode the mixture, and exhaust the burnt gases without the em- 45

ployment of other valves, the piston head 19 in reality being a valve itself.

What is claimed is:—

In a valveless two cycle internal combustion engine the combination of, a primary cylinder provided with spaced communication openings adjacent the head end thereof and forming a fuel by-pass, a double-walled 50 secondary cylinder disposed concentric and disposed within the lower crank end thereof, a cylindrical piston slidably disposed between and contacting with the inner and outer peripheries of the primary and secondary cylinders respectively, the space between the head of the piston and primary cylinder, piston and secondary cylinder, forming compression and combustion chambers respectively, said primary cylinder provided with, a fuel inlet port, a spark plug port, and an exhaust port, said cylindrical piston provided with inlet and exhaust ports, the full outstroke of said piston adapted to uncover the primary cylinder fuel inlet port 55 and bring the same into communication with the said compression chamber, and to align the piston inlet with the cylinder spark plug, the full instroke of the said piston adapted to cover the spark plug port, and the primary cylinder fuel inlet port, and to align the lower by-pass opening and the piston inlet port to bring the compression and combustion chambers into communication and to align the exhaust ports of the piston and 60 cylinder, and a water jacket surrounding the said primary cylinder and communicating with the double-walled secondary cylinder, to thereby provide for the circulation of a cooling medium around the walls of the 65 primary cylinder, around the walls and head of the secondary cylinder.

In testimony that I claim the foregoing as my own, I have hereto affixed my signature in the presence of two witnesses.

CARL W. KNIGHT.
